UNITED STATES PATENT OFFICE.

LEO EUGENE TROSCLAIR, OF NEW ORLEANS, LOUISIANA.

GAS-REGULATING VALVE.

Application filed January 21, 1922. Serial No. 530,981.

To all whom it may concern:

Be it known that I, LEO EUGENE TROSCLAIR, a citizen of the United States, and a resident of New Orleans, in the parish of Orleans and State of Louisiana, have invented certain new and useful Improvements in Gas Regulating Valves, of which the following is a specification.

My invention relates to improvements in valves, and it consists in the constructions, combinations and mode of operation herein described and claimed.

An object of the invention is to provide a valve which is operated by varying pressures of steam in a boiler to automatically diminish or increase the flow of gas, but at the same time prevent the flow of gas to a burner from being entirely stopped, this last provision functioning like a pilot.

Other objects and advantages will appear in the following specification, reference being had to the accompanying drawings, in which—

The figure is a longitudinal section of the improved valve.

This valve is an improvement on my patent for gas regulating valves, 1,407,963 of February 28, 1922. A description of the old construction will serve to emphasize the improvement. A pipe 1 conducts gas to the casing 2 of a valve head 3, and from the casing flows to a gas burner by way of the pipe 4. The burner may be of any desired type. Its purpose is to heat the water in a boiler.

Steam from this boiler enters the left side of the casing 2 by way of a pipe 5 so that its pressure is exerted against a flexible diaphragm 6. The diaphragm is clamped between sections of the casing 2 dividing the casing into high and low pressure compartments. The head of the valve 3 in the low pressure compartment engages the right side of the diaphragm. A spring 7 presses the valve in this engagement. The spring bears against a screw plug 8 in the threaded end of the barrel 9 of the casing 2. The patent referred to will disclose the use of an adjustable by-pass between the casing 2 and the barrel 9. This by-pass is dispensed with, but its function is retained and the construction of the improvement by which this function is retained, constitutes the invention. The left end of the barrel 9 is shaped into a valve seat 10 which is beveled, as shown, instead of being flat

as in the co-pending application. The inner surface of the head 3 is correspondingly beveled at 11. A guide 12 in the bore of the barrel 9 supports the valve 11 and its associated parts.

There are times when it may be desired to have the bevel 11 rest on the seat 10. There are other times when this may not be desirable, and provisions are made to meet both instances. The valve body is internally threaded at 13 its full length. A stem 14 is screwed into the threaded bore 13 so that the left end of the stem engages the diaphragm 6. The purpose of this arrangement is to permit an adjustment after the valve 11 has been ground, and obviously the stem 14 must be adjusted in respect to the diaphragm 6 in order to compensate for the material ground away from the face 75 of the valve.

The stem 14 therefore always bears a fixed relationship to the diaphragm 6, while the valve head 3 varies in position in respect to the diaphragm 6 as it is ground away. 80 A check nut 15 fixes the stem 14 in its newly adjusted positions.

A screw 16 limits the movement of the valve 3 toward the right under the pressure of steam at the left of the diaphragm 6. 85 The adjustments of the screw 16 in the plug 8 are fixed by a check nut 17. If the screw 16 is adjusted in far enough, the valve 3 will be prevented from seating at 10, and therefore a passage from the pipe 90 1 to the pipe 4, hence to the burner, is left open. This open passage functions as a pilot for the burner when most of the gas is cut off and steam in the boiler is under high pressure. The function of the pilot 95 may be disposed with by simply adjusting the screw 16 out so that the surfaces 11 and 10 may contact under high steam pressure, at which time care must be taken to cut off the flow of gas at the cock 18. 100

I claim:

1. A gas casing including a barrel ending in a seat, a valve associated with the seat, a valve body of which said valve is a part situated in the barrel, a stem adjustable in the valve body to compensate for grindings of the valve, a plug in the end of the barrel opposite the seat, and a set screw in said plug to cooperate with the end of said stem. 105

2. The combination of a gas casing having a diaphragm receiving steam pressure

2. at one side, a barrel included in the casing and having a seat, a valve engaging the diaphragm but also adapted to engage the seat, a stem carried by the valve, a plug in the end of the barrel, a spring resting against the plug pressing the valve toward the diaphragm, a set screw in the plug to be engaged by the stem to limit the movement of the valve toward the seat, and means permitting adjustments of the stem of the valve to compensate for grindings of the valve when the adjustments of the screw are such that the valve repeatedly engages the seat.
3. The combination of a valve seat, a valve adapted to engage the seat, an adjacent diaphragm adapted to move the valve toward the seat, and a stem upon which the valve is adjustable extending through the valve into engagement with the diaphragm to preserve a fixed relationship between the stem and diaphragm to permit grindings of the valve and prevent interference with the functioning of the diaphragm.
4. The combination of a valve seat, a valve which is movable in respect to the seat, means which is adapted to remain stationary in respect to the valve seat and thus constitute an abutment, means which is carried by the valve and is adapted to en-
- gage the abutment so as to check the seating movement of the valve and leave a by-pass, and means by which the valve may be adjusted upon said carried means so as to change the relationship of the valve to the seat.
5. The combination of a valve seat, a diaphragm situated in front of the valve seat and adapted to move in respect thereto, a stem contacting the diaphragm at one end, means which provides an abutment with which the other end of the stem is adapted to contact, a valve carried by the stem, means by which the first end of the stem is kept in permanent contact with the diaphragm and by which the valve is kept from the seat, and means on the stem by which the valve may be adjusted thereon in respect to the seat, stem and diaphragm.
6. The combination of a barrel having a valve seat, a valve adapted to engage the seat, abuttable means carried by the barrel adapted to check the seating movement of the valve to leave a by-pass, means carried by the valve adapted to engage said abuttable means, and means on said valve-carried means enabling adjustment thereof in respect to said abuttable means to compensate for a grinding of the valve surface.

LEO EUGENE TROSCLAIR.
